REFRIGERATOR

Ray C. Sandin, Northbrook, Ill., assignor to General Electric Company, a corporation of New York

Application October 27, 1954, Serial No. 32,836

Term of patent 14 years

(Cl. D67—3)

To all whom it may concern:

Be it known that I, Ray C. Sandin, a citizen of the United States, residing at Northbrook, in the county of Cook and State of Illinois, have invented a new, original, and ornamental Design for a Refrigerator, of which the following is a specification, reference being had to the accompanying drawing forming a part thereof:

The figure is a front perspective view of a refrigerator embodying my new design. The respective side walls are identical.

I claim:

The ornamental design for a refrigerator, substantially as shown and described.
